UNITED STATES PATENT OFFICE

HERMAN HERZOG, JR., OF GAINESVILLE, FLORIDA.

CHARGE-HEATING ATTACHMENT.

1,261,387.

Specification of Letters Patent. Patented Apr. 2, 1918.

Application filed December 6, 1917. Serial No. 305,805.

To all whom it may concern:

Be it known that I, HERMAN HERZOG, Jr., a citizen of the United States, residing at Gainesville, in the county of Alachua and State of Florida, have invented certain new and useful Improvements in Charge-Heating Attachments, of which the following is a specification.

This invention relates to improvements in charge heating attachments for combustion engines and it is the principal object of the invention to provide a device for utilizing the heat of the exhaust manifold of an engine for heating the explosive mixture discharged from a carburetor by way of the intake manifold into the cylinders of the engine, thereby, assisting vaporization at the carburetor discharge nozzle and also aiding in breaking up the minute globules of sprayed fuel by raising the temperature of the mixture and preventing condensation of the heavier hydrocarbons on the walls of the intake manifold.

Other objects will be in part obvious and in part pointed out hereinafter.

The improvements in the details and arrangement of parts will be apparent from an inspection of the accompanying drawings, in connection with the specific description hereinafter contained, and wherein the preferred embodiment of the invention is disclosed for the purpose of imparting a full understanding of the same.

In the drawings:—

Fig. 1 is a side elevation of the attachment as applied to an engine, and,

Fig. 2 is a perspective of the same.

Having more particular reference to the drawings, in connection with which like reference characters will designate corresponding parts throughout the several views, E represents the combustion engine provided with the charge heating attachment, the said engine having the intake and exhaust manifolds *i* and *e* arranged upon one side thereof. As will be readily understood, during functioning of the engine E, the exhaust manifold *e* will become heated to a high degree, by reason of the passage of the heated spent gases passing from the cylinders into the atmosphere.

The improved charge heating attachment comprises a plate having a body portion 1 and transversely extending arms generally indicated by the numeral 2, which arms, as will be noted, are arranged in spaced re-

lations and are adapted to contact with portions of the adjacent walls of the intake and exhaust manifolds *i* and *e* respectively. A longitudinally disposed arm or extension 3 is also formed on one end of the body portion 1 of the plate and is adapted to lie adjacent and contact with a portion of the intake manifold *i*, obviously, the vertical portion thereof which serves as means for effecting a connection between a carburetor and the engine E. Openings are formed in the extension 3 and are adapted to receive the screw threaded extremities of a U-shaped clamping bolt 4 therein, whereupon locking nuts or other suitable securing means 5 are turned into engagement with the said screw threaded extremities and have bearing on the outer face of the extension 3. In this way, the heating attachment will be securely held in position with relation to the intake and exhaust manifolds of the engine and as a consequence, when the exhaust manifold *e* becomes heated, such heat will be radiated by way of the attachment to the intake manifold *i*, thereby affording means for raising the temperature of the explosive mixture discharged into the same from the carburetor.

From the foregoing, it will be readily understood by persons skilled in the art that with my improved attachment, I am enabled to cause vaporization of the explosive mixture at the carburetor discharge nozzle and also, to cause the breaking of the minute globules of sprayed fuel due to the raising of the temperature of the same. Further, condensation of the heavier hydrocarbons upon the walls of the intake manifold will be prevented, due to the fact that the temperature of the same is materially raised.

Manifestly, the construction shown is capable of considerable modification and such modification as is within the scope of my claims, I consider within the spirit of my invention.

I claim:—

1. A device of the character described, including a plate having transversely disposed extensions formed thereon in spaced relation, said extensions and plate being adapted to contact with the intake and exhaust manifolds of a combustion engine, and means for removably securing the plate to said manifolds. 105

2. A device of the character described including a heat conducting plate having a

plurality of spaced transversely disposed arms formed integral therewith, a longitudinally disposed arm formed integral with one end of said plate, and means for detachably securing the plate to the intake and exhaust manifolds of a combustion engine.

3. A device of the character described including a heat conducting plate having spaced laterally extending arms formed in-

tegral with the marginal portions thereof, a longitudinally disposed extension formed integral with one end of said plate, and means for detachably securing the plate to the intake and exhaust manifolds of a combustion engine.

15

In testimony whereof, I affix my signature hereto.

HERMAN HERZOG, JR.
